UNITED STATES PATENT OFFICE

JACOB A. ALTMAN, OF LOS ANGELES, CALIFORNIA

DESIGN FOR A COMBINED AUTOMOBILE HOOD AND RADIATOR

Application filed May 9, 1930. Serial No. 35,548. Term of patent 14 years.

To all whom it may concern:

Be it known that I, JACOB A. ALTMAN, a citizen of the United States, residing at Los Angeles, in the county of Los Angeles and State of California, have invented a new, original, and ornamental Design for Combined Automobile Hood and Radiator, of which the following is a specification, reference being had to the accompanying drawing, forming a part thereof.

Figure 1 is a perspective of a combined

automobile hood and radiator, showing my new design.

Figure 2 is a front elevation of the combined automobile hood and radiator shown in Figure 1.

I claim:

The ornamental design for a combined automobile hood and radiator, as shown.

Signed at Los Angeles, California, this 2nd day of May, 1930.

JACOB A. ALTMAN.
